BRANDING MACHINE

Stanley B. Neff, Sandy, and William A. Neff,
Riverton, UtahRefiled for abandoned application Serial No.
488,632, October 14, 1930. This application
March 6, 1933. Serial No. 659,818

7 Claims. (Cl. 101—35)

This invention relates to a branding machine, and more particularly, a branding machine for fragile articles having substantially spherical, elliptical or other surfaces, such as eggs, though not necessarily limited thereto.

The principal objects of the invention are:

First. To be operative to imprint eggs or other fragile articles positively, yet with an impact so light that no mechanical injury results.

Second. To be rapid in action.

Third. To be simple, durable and compact in construction.

The features of this invention, for which the protection of Letters Patent of the United States is desired, are collectively grouped in the claims concluding this specification.

In the drawing, which illustrates one embodiment of the present invention,

Fig. 1 represents a horizontal section taken on line 1—1, Fig. 2, showing the operating parts of the mechanism in plan:

Fig. 2, a vertical section taken substantially on the line 2—2 in Fig. 1, parts in the background being omitted;

Fig. 3, a section similar to Fig. 2, showing the operating parts in an alternate position;

Fig. 4, a section taken on line 4—4, Fig. 1, reflected from a mirror plane;

Fig. 5, a vertical section taken on line 5—5,

Fig. 1, reflected from a mirror plane;

Fig. 6, an elevation of the branding element viewed from the line 6—6 in Fig. 3, and drawn to an enlarged scale; and

Fig. 7, an electrical diagram.

Referring to the drawing, numeral 10 indicates a casing or housing preferably made of sheet metal, and extending upwardly from a base 12 to any convenient height. The base may be made of a slat of electrically non-conductive material, such as wood or slate, and have mounted upon it a standard 13 in which may be pivotally supported at 14, a branding member 15. The branding member may be in the form of a swinging lever having preferably a long arm 15—1 and a short arm 15—2.

Flexibly connected to the short arm 15—2, for example, by means of a pivoted link 16, is a bar 17, which at its opposite end may be rigidly fastened in a core 18. This core, in conjunction with a coil 19, forms a solenoid operative when energized, to pull the bar 17 in the direction of the arrow in Fig. 2. In so moving, the core 18 serves to compress a spring 20 which reacts against a yoke 21 and becomes effective when the solenoid 55 is deenergized, to return the core to substantially

the position indicated in Fig. 2. Yoke 21 may be rigidly attached to a frame 24, preferably made of insulating material, which also supports coil 19.

The arm 15—1 of the branding member may carry an imprinting element which may consist of a rubber printing strip or stamp 30, capable of accommodating the varying curvatures of eggs. Ink, or some other marking substance, may be supplied to the printing strip by means of a pad or fountain 34 carried on an inking member 35, which latter, in the retracted position of arm 15—1, overlaps the printing face.

The inking member may consist of a pad carried on an arm pivoted at 36 on the frame 24 and inclined to the path of core 18, so that in conjunction with an actuator, which may consist of a staff 37 secured in bar 17, a cam action is obtained which serves to lift the inking pad out of the way of the stamp as the latter is rising to the branding position, shown in Fig. 3, 75 due to the forward movement of the core. As the core is returning to its normal or retracted position, gravity acts to bring the inking pad back to its bearing against the face of the rubber stamp. A stop or rest 39 may be provided for 80 the disappearing branding member 15 in its retracted position, indicated in Fig. 2. It will be noted that in the forward movement of the core, link 16 first oscillates around pivot 16—1 so as to allow a small interval of time for the inking 85 member to be raised in advance of the branding member.

Rigidly secured on rod 17 is an arm 25 carrying an insulating button 26 adapted to strike a spring contact member 27, which in conjunction 90 with a terminal 28, closes an electrical circuit for a purpose presently to be explained.

An aperture 40 may be conveniently located in the casing, the casing being preferably a relatively stationary structure with regard to the branding mechanism proper, while a switch 41 having a finger 41—1 is operatively contiguous to the aperture, the finger being slidably mounted in a bracket 42 secured to the casing.

Finger 41—1 contacts a switch arm 41—2 preferably made of insulating material, and pivoted to the base 12 at 46. The arm 41—2 may carry a switch blade 41—3, which in conjunction with a contact member 41—4, forms part of the main circuit. Arm 41—2 may be normally held in the 105 open position of the switch by means of a tension spring 48.

A feature of this invention is the provision of a positioner and stop, whereby that portion of an egg or other rounded body presented to the 110

face of the printing stamp, is brought into the proper position, and into alignment therewith. Obviously, unless there is proper alignment, an imperfect impression will result. The required condition then, is that a normal drawn to the curved face of the body, shall also be substantially normal to the printing face. In the present instance, this requirement is met by that portion of the casing which defines the aperture 40. 10 It will be clear however, that any construction which provides at least three points of bearing for the rounded body, in a plane contiguous to the portion of its curved surface to be impressed, and at the same time causes this portion to protrude beyond the bearing plane towards the printing face, will fulfill the required condition.

At 53, a circuit breaker may be provided in the form of an electromagnet 53-1 acting upon an armature 53-2, which carries a contact finger 20 53-3 adapted to contact a spring member 54. The latter may be so constructed and positioned that when the circuit is closed at 54-1 by the finger 53-3, then the contact at 54-2 with terminal 56 will be broken, thereby closing and opening different circuits, as will be explained hereinafter.

An incandescent lamp 58, connected in any well known manner, casts a beam of light through the aperture 40 so that when an egg 51 is placed 30 in the apertures, the light will fall on it.

In operation, as the user brings an egg 51 against finger 41, and to its bearing in the aperture 40, the light shines through the egg, enabling him to candle it, while finger 41, pushed 35 by the egg, completes the electrical circuit, thereby actuating the branding element, as will now be explained.

When the main circuit, including incoming lead 60 and outgoing lead 61, is closed, current flows 40 through conductor 62, coil 19, conductor 63, terminal 56 and finger 54. This energizes coil 19 and causes core 18 with bar 17 to be pulled in the direction of the arrow, thereby raising the inking pad and flipping the branding stamp up 45 against the egg, the latter being indicated in the initial position in dotted lines 51, Fig. 1, and in the final position, in dotted lines 51-1, Fig. 3. After the stamp has impressed the egg, it is automatically retracted in the manner described 50 below.

When the core reaches the end of its stroke, the insulating pad 26 strikes the spring 27 and causes 55 it to touch terminal 28, thereby completing the circuit through the circuit breaker 53. In this circuit, the current travels from terminal 41-4 through conductor 65, coil 53-1, conductor 67, contact 27, terminal 28, conductors 68 and 63, terminal 56, finger 54, and out through wire 61. Energizing this circuit energizes coil 53-1, and 60 draws armature 53-2 against its pole piece 53-4, thereby causing contact member 53-3 to touch finger 54 at point 54-1, at the same time opening the first circuit at 54-2. This deenergizes coil 19 and permits spring 20 to come into action 65 to return the core, branding arm and inking pad to their normal positions. This action, at the same time, changes the flow of the current from the coil 53-1 through conductor 67, contact 27, and so on, so that the current will now flow from 70 coil 53-1 through conductors 67 and 57, contacts 53-3 and 54-1, finger 54, and out through lead 61.

Coil 53-1 will remain thus energized as long as the egg is in the positioner, keeping contacts 75 41-3 and 41-4 closed. As soon as the egg is

removed from the positioner, contacts 41-3 and 41-4 will open, due to the action of spring 48, thereby opening all the circuits and allowing the armature 53-2 to drop away from the pole piece. This disengages contacts 53-3 and 54-1 and restores contact at 54-2, leaving coil 19 ready for another cycle of operation when the next egg is placed in the positioner. 80

The term positioner, as used in the present instance, applies to the casing wall in which aperture 40 is defined. Broadly, this term could mean any element against which an egg or other object may be held manually, to bring it into a definite position for registry with the branding member in its imprinting contact with an egg. The positioner also guides the egg into the proper contact with the operating switch 41. The branding member may be referred to as an imprinter. 85 90

The electric lamp, out of which the candling beam of light proceeds, may be connected in parallel with the electrically actuated branding mechanism, as indicated in diagram in Fig. 7, or it may be connected in series therewith (not shown). The general operating results in both 100 cases, are substantially equal, though the co-operative relationship is more intimate in the latter case. 95

It will be seen that there are three interconnected circuits, as follows: (a) one for energizing 105 the solenoid; (b) one for energizing the circuit breaker; (c) one for keeping the circuit breaker closed until the egg is taken out of the positioner.

By keeping the circuit breaker closed during the time period that the egg keeps the operating 110 switch closed, burning out of the solenoid coil is prevented, and in case of a series hook-up, the candling lamp is kept energized during this time period, instead of being merely flashed on momentarily. 115

For properly timing the action of printing arm 17, it is desirable that switch arm 41-2 shall have such a travel that contact 41-3 will not close the circuit until the object to be marked, is almost seated in aperture 40. 120

While the branding mechanism and stop member can be used separate from the candling light, it is to be noted that their use in conjunction with the latter as herein described, is especially advantageous and accomplishes a new result, 125 because one handling of eggs by the operator, both candles and marks the eggs, thus saving approximately one half the time heretofore required in performing these two necessary items in preparing eggs for the market. 130

To this conjunctive end, the printing member 17 is made disappearing in character, that is to say, it remains in contact with an egg in front of the light for only a very small period of time, and then disappears, leaving the space between 135 the egg and the light absolutely clear, since no opaque object must intervene during candling.

We do not claim the light as a part of our invention, but we do claim a branding mechanism especially adapted for use in connection with a 140 candling light as set forth herein.

Furthermore, we are aware of the U. S. patent to Pratt et al., Number 945,802, which shows a sealing stamp operated through an electric switch actuated by contact of an article to be stamped; 145 also, of the U. S. patent to Willard, Number 1,236,801, which shows a cupped cushion for oranges as part of a hand-operated stamp.

Therefore, we do not claim an electrically operated printing mechanism, nor a stop member, 150

broadly, but restrict our invention to operating mechanism and stop members of the types herein disclosed.

It is to be noted however, that the elongated "slot 31" in Willard's patent, does not provide a bearing having at least three points lying in a plane intersecting a spherical object or other object of revolution, as in our device, since such an object, in Willard, would touch only two points opposite each other along the long sides of the slot, and such two-point contact would allow the object to be rolled lengthwise of the slot indefinitely, hence causing an imperfect impression.

15 This application is a substitute for, and a continuation in part, of an application filed by us on October 14, 1930, Serial Number 488,632.

While a specific embodiment of this invention is herein shown and described, it is to be clearly understood that variations within the scope of the accompanying claims, may be resorted to without jeopardizing our patent protection.

Having fully described our invention, what we claim is:

25 1. A branding machine for objects, such as eggs and the like, including in combination, an object stop having at least three points lying in a plane, said plane intersecting the object so that a portion of said object protrudes beyond said plane, a printing stamp disposed to impress the protruding portion of the object on the opposite side from that where the object is brought against said stop, and mechanism disposed to be contacted by the protruding portion 35 of said object whereby the branding mechanism is caused to imprint said protruding portion.

2. A branding machine for objects such as eggs and the like, including in combination, a stop lying substantially in a plane, intersecting the object, a pivoted branding member having a printing face disposed to be swung into contact with the portion of the object protruding inwardly from said plane, a solenoid operative to impart motion to the branding member, and an electric switch disposed for contact by said protruding portion of the object; said switch being in the circuit with said solenoid.

3. A branding machine for eggs and the like,

50

55

60

65

70

75

said machine being designed for use in conjunction with a candling light, including in combination, an egg positioner in front of said light, and a disappearing printing member disposed for operation between the egg and the candling light.

4. A branding machine, including in combination, a structure having a stop for spherical or like objects, said stop lying substantially in a plane and disposed to allow a portion of the object when engaged by the stop to protrude beyond said plane, an electric switch disposed for contact by the protruding portion, and an electrically operated printing mechanism having a disappearing printing arm for impressing said protruding portion, said printing mechanism being in circuit with said switch.

5. A branding machine, including in combination, a swinging lever having a printing face normally retracted, an arm having an inking pad overlapping the retracted printing face, and a solenoid having a core for actuating the inking arm and the printing lever in operative sequence, relative to each other.

6. A branding machine, including in combination, a branding member having a printing position and a retracted position, a solenoid operative to cause movement of the branding member from the retracted position to the printing position, an inking member contacting the face of the branding member in the retracted position, and an actuator effective to control movement of said inking member during the operating cycle of the branding member.

7. A branding machine, including in combination, a switch positioned so as to be operatively contacted by an object such as an egg, a branding member having a branding position in operative proximity to said switch, a solenoid having a core connected to said branding member, an inking member positioned to contact said branding member, and an actuator positioned to impart motion to said inking member; said actuator being mounted on the core structure of the solenoid, and the solenoid being in circuit with said switch.
